UNITED STATES PATENT OFFICE

108,959

DESIGN FOR AN ORNAMENTAL PLATE FOR A CASKET OR ANALOGOUS ARTICLE

Raymond Larson, Chicago, Ill., assignor to Central Metallic Casket Co., Chicago, Ill., a corporation of Illinois

Application December 24, 1937, Serial No. 73,861

Term of patent 7 years

To all whom it may concern:

Be it known that I, Raymond Larson, a citizen of the United States, residing at 2207 North Lamon Avenue, Chicago, in the county of Cook and State of Illinois, have invented a new, original, and ornamental Design for an Ornamental Plate for a Casket or Analogous Article, of which the following is a specification, reference being had to the accompanying drawing forming part thereof.

Figs. 1 and 2 illustrate respectively, a front elevation and a top plan view of an ornamental plate for a casket embodying my new design, and

Fig. 3 is an end view of same.

I claim:

The ornamental design for an ornamental plate for a casket or analogous article as shown.

RAYMOND LARSON.
